UNITED STATES PATENT OFFICE.

WALTER PERCY WIDDOWSON, OF LONDON, ENGLAND.

INTERNAL-COMBUSTION-ENGINE FUEL-INJECTION DEVICE.

Application filed August 8, 1921, Serial No. 490,639, and in Great Britain May 5, 1920.

(GRANTED UNDER THE PROVISIONS OF THE ACT OF MARCH 3, 1921, 41 STAT. L., 1313.)

This invention relates to internal combustion engines of the type in which liquid fuel is injected into the combustion chamber, at or near the end of the compression stroke 5 by means of a fuel injection pump, and in which a fuel injection pump pumps the liquid fuel to a fuel injection valve, which is opened by the pressure of the liquid fuel, or other suitable means, the amount of liquid 10 fuel injected into the combustion chamber being regulated by a release or "spill" valve which is opened by control or governing mechanism at a variable or fixed point in the stroke of the fuel pump plunger, thereby 15 "spilling" the fuel for the remainder of the stroke of the plunger.

Heretofore it has been proposed in a forced liquid fuel supply to internal combustion engines, to provide two by-pass valves 20 designed to be operated at different periods of the forcing stroke of the oil pump, the two valves being in some cases substituted by a single duplex valve.

The present invention comprises an internal combustion engine liquid fuel injection device having a spring-loaded injection valve and a single spill valve or by-pass in a passage communicating with the fuel reservoir, wherein the by-pass is not brought 30 into use until after sufficient fuel has been forced through the injection valve, and a continuous pressure circuit established between the pump and the spill valve.

The release or spill valve may be placed 35 on the body of the fuel injection valve, or in any other convenient position, and is placed in communication with the fuel injection valve pump through the injection valve. By having the spill valve arranged to let the 40 oil furnished by the remainder of the piston stroke to pass through the injection valve chamber, this chamber is continuously washed out and also slightly cooled.

The system may be provided with a liquid 45 fuel strainer arranged between the fuel pump and the injection valve.

An embodiment of the invention is illustrated by the accompanying drawing wherein *a* is the combustion chamber of an internal combustion engine, *b* the fuel injection valve, *1* the body thereof, *c* the spill valve, *d* the liquid fuel plunger, and *18* the cam.

The fuel injection valve body *1* is screwed

into an opening in the engine casting leading 51 to the combustion chamber, and is provided with an inlet passage *2*, and an outlet passage *3*, leading respectively to and from a pressure chamber *4* wherein fluid pressure 56 of the liquid fuel is exerted upon a shoulder 50 on the spindle of the valve *b*. This spindle is loaded by a spring *6* in the known manner so that the valve *b* will not be raised from its seat until the pressure in the delivered liquid fuel rises above the amount 61 necessary to overcome load of the spring *6*.

The inlet passage *2* of the valve casing is connected by a delivery pipe *7* to the delivery valve *8* of the liquid fuel pump, and the outlet passage *3* is connected by a return pipe *9* to the upper side of a spill valve *c*. This spill valve is held on its seat in the valve body *12* by a spring *10*, and has a spindle extending through a stuffing box *11*. 70 This valve spindle is arranged in line or coaxial with a valve operating rod *13* pivoted to a lever *14* secured to a shaft *15* on which is secured the pump operating rocking lever *16*. One end of this lever is provided with a roller *17* adapted to bear on a cam *18* secured on the cam shaft *19* of the engine; the other end of the lever *16* bears in a slot in the pump plunger *d* in such a manner that when the roller *17* is raised by the cam *18*, the other end of the lever *16* will force the 80 plunger *d* into its barrel against the action of a return spring *20*. Strainer *26* is set under plunger *d* to act on the oil before it passes to valve *8*.

The underside of the spill valve *c* is connected by a pipe *21* to the underside of the suction valve *22* of the fuel pump. The piston *26* supporting the spring *10* on the spindle of the valve *c* is perforated at *27* to admit fluid under pressure to both sides of the piston. The suction valve *22* is placed in communication with the liquid fuel reservoir by a suction pipe *25*.

A control rod *23* is adapted to move at 90 right angles to the valve spindle *11* between the end thereof and the end of the valve operating rod *13*, and has an inclined member *24* attached thereto adapted to engage, on one side the end of the spindle *11* and on the other, the end of the valve rod *13*, so that when the inclined member *24* moves to the right it will reduce the distance between it and the ends of the valve spindle *11* and

valve rod 13, and so cause a variation in the time of engagement between the said spindle and rod according to the extent of longitudinal movement of the governing or control rod 23.

It will be readily understood from the above description that the fuel pump operates in the well known manner, so that on the down or delivery stroke of the plunger 10 upon the rotation of the cam shaft 19, liquid fuel is compressed in the pipes and passages, until the pressure therein rises to that at which the injection valve *b* is designed to open. After the opening of the valve *b* the 15 continued movement of the cam 18 causes the valve rod 13 to open the release or spill valve *c*, and on the opening of this valve the fuel pressure is released thereby allowing the injection valve to close automatically, 20 and for the remainder of the fuel pump stroke the fuel is discharged through the passages 2 and 3 in the injection valve body and the pipe 9 and spill valve *c* and pipe 21 to the suction pipe 25 of the fuel pump.

What I claim and desire to secure by Letters Patent is:—

In an internal combustion engine liquid fuel injection device, in combination, an injection valve structure comprising a valve chamber having an injection outlet and a valve controlling said outlet, said valve having a surface exposed to the pressure in said chamber to be opened thereby, a spring resisting opening movement of said valve, a fuel pump connected with said chamber to supply fuel thereto under pressure, a spill valve connected with said injection valve chamber, operating means for said pump, and means operating in synchronism with said pump operating means for opening said spill valve during the end of each pressure stroke of said pump whereby said valve chamber will be relieved of pressure and said injection valve allowed to close, said spill valve at other times being closed.

In witness whereof I affix my signature.

WALTER PERCY WIDDOWSON.
